UNITED STATES PATENT OFFICE.

ROY RAY FOGELSONGER, OF CLARENCE, NEW YORK.

COIN-CONTROLLING MECHANISM.

Application filed May 16, 1923. Serial No. 639,379.

To all whom it may concern:

Be it known that I, ROY RAY FOGELSONGER, a citizen of the United States, residing at Clarence, in the county of Erie 5 and State of New York, have invented a new and useful Improvement in Coin-Controlling Mechanism, of which the following is a specification.

This invention relates to a coin apparatus 10 for controlling the operation of a vending apparatus, such for instance an as apparatus for dispensing newspapers, confectionery or other merchandise by the introduction of coins in a slot or conduit leading 15 to the coin apparatus which controls the operation of the dispensing mechanism.

At the present time some kinds of merchandise are sold to the public for two coins, for instance newspapers which cost two 20 cents, and as two cent pieces at the present time are rare and the coinage of the same has been discontinued it becomes necessary to use two separate pennies when purchasing a newspaper of this price. In organizing 25 a coin apparatus which is more particularly designed for dispensing or vending newspapers which requires the deposit of more than one coin to operate the mechanism it is necessary to make provision for 30 preventing the operating of the vending apparatus until the required number of coins have been deposited in the apparatus, and it is also desirable to so organize this apparatus that a party placing an insufficient 35 number of coins in the apparatus can recover the same if he does not desire to lose the coins already placed in the apparatus.

It is therefore the purpose of this invention 40 to provide simple, reliable and efficient means whereby a vending apparatus may be operated manually after the required number of coins have been placed in the machine, but which will prevent its operation 45 if a deficient number of coins have been deposited in the apparatus, and also enable the person depositing such coins to recover the same if he so desires.

In the accompanying drawings: Figure 50 1 is a sectional top plan view of a coin apparatus embodying my invention and showing the parts in the position which they occupy preparatory to receiving the 55 coins from the customer. Figure 2 is a vertical longitudinal section of the same. Figure 3 is a sectional view similar to Fig-

ure 1 showing the position of the parts when at attempt is made to operate the apparatus manually without introducing any coin into the same. Figure 4 is a longitudinal section of the same corresponding to Figure 2. Figure 5 is a horizontal section similar to Figure 1 showing the position of the parts when only one coin is introduced into the machine. Figure 6 is 60 a vertical longitudinal section of the same corresponding to Figures 2 and 4. Figure 7 is a sectional view similar to Figures 1 and 3 but showing the parts in the position which they occupy when two coins of 70 the proper thickness have been introduced into the machine and the vending mechanism associated therewith has been operated.

Figure 8 is a vertical longitudinal section of the same corresponding to Figures 2, 4 and 6. 75

Similar characters of reference refer to like parts throughout the several views of the drawings.

This coin apparatus may be used for controlling the mechanism which dispenses any suitable commodity such as newspapers, confectionery, liquids or the like, which vending mechanism however forms no part of this invention and therefore only a lever 80 10 is shown in the drawings as the element of the vending apparatus which must be actuated in order to cause the vending mechanism to discharge an article which is to be sold. In the present instance this 85 lever is arranged in any suitable manner within a casing which encloses the vending mechanism and which, as shown in the drawings, comprises a bottom 11, an upright front wall 12 and a rear wall 13. 90 The operating lever 10 in the present construction is assumed to actuate the vending mechanism for discharging a piece of goods from the casing when this lever is moved forwardly, but when the same is moved 95 backwardly the motion is idle and only prepares the vending mechanism for effecting a discharge of the goods from the machine during the subsequent forward movement of this lever. 100

My improved coin mechanism for controlling the operation of the operating lever 10 of the vending mechanism is constructed as follows:

Slidable horizontally through an opening 14 in the front wall of the enclosing casing are two controlling bars which form 110

part of the coin controlling mechanism, an inner or rear bar 15 which is arranged partly within the enclosing casing and is pivotally connected at its inner or rear 5 end by means of a pin 16 with the free end of the operating lever 10, and a front or outer bar 17 which reaches from the interior to the exterior of the casing and is provided at its outer or front end with a 10 handle 18 of any suitable character for manipulating this last mentioned bar.

The inner or rear controlling bar is provided at its front end with a bearing surface 19 which is preferably of concave form 15 and at times forms part of a coin pocket adapted to receive the coins which render it possible to actuate the operating lever 10 through the medium of the controlling bars 15 and 17.

On the under side of the front 20 end of the inner or rear controlling bar the same is provided with a clearance space or recess 20 which is equal in height to the thickness of one of two coins which will operate the apparatus, while that part of 25 the front end of the rear controlling bar above the recess 20 is also equal to one of two coins suitable for operating the apparatus. About midway of the length of the rear controlling bar the same is provided on 30 its opposite longitudinal edges with two lugs or projections 21, each of which forms a rearwardly or inwardly facing shoulder 22 and an outwardly or forwardly facing shoulder 23 on the rear controlling bar, as 35 shown in Figures 1, 3, 5 and 7. On its upper side and within the enclosing casing the rear controlling bar is provided with a cam 24 which is arranged about midway of the length of this bar.

The outer or front controlling bar 17 is provided with a longitudinal slot, the front portion 25 of which is comparatively narrow and the longitudinal sides of which engage with opposite longitudinal sides or 40 edges of that part of the rear controlling bar in front of its lugs 21, while the rear part 26 of the longitudinal slot in the front controlling bar is comparatively wide and its inner longitudinal walls or sides engage 45 with opposite sides of the lugs 21 on the rear controlling bar and form on said front controlling bar two inwardly facing front shoulders 27 which are adapted to engage with the forwardly facing shoulders 23 on 50 the rear controlling bar and two forwardly facing shoulders 28 see Figure 1 which are adapted to engage with the rearwardly facing shoulders 22 on the rear controlling bar. Immediately in front of its rearwardly facing shoulders 27 the front controlling bar is provided on opposite sides of the front 55 part of the rear controlling bar with two concave notches 29 of curved form, which notches are adapted at times to be arranged 60 concentrically with the bearing face 19 of

the rear controlling bar and form therewith part of the coin pocket which receives the coins, whereby the front and rear controlling bars are coupled in the proper manner to enable the vending machine to be actuated and deliver the goods to the customer. The overlapping parts of the front and rear controlling bars are arranged within a guideway 30 formed in a bracket 31 which is secured to the front side of the enclosing casing and projects forwardly therefrom. This bracket is provided on the outer part of its upper side with a coin receiving slot or inlet opening 321 through which the intended purchaser may introduce his coins into the apparatus for the purpose of operating the dispensing mechanism.

Within the enclosing casing is arranged a mechanism which prevents the outer or front controlling bar from moving inwardly its full extent excepting when the proper number of coins have been introduced into the controlling apparatus. These means comprise a vertically swinging latch 311 arranged over the inner or rear part of the rear controlling bar and pivoted at its rear end by means of a horizontal pivot 32 on the rear wall of the casing while its front end is adapted to be engaged by the incline surface of the cam 24 on the rear controlling bar, and the under side of this latch is provided with one or more stop shoulders 33, preferably two in number which are arranged on opposite sides of the rear part of the rear controlling bar and are adapted to be engaged by the inner or rear ends of the branches of the front controlling bar. The inner parts of the front and rear controlling bars are preferably supported on their under sides by means of a shelf or guideway 34 secured to the adjacent portion of the bottom of the casing. After goods have been ejected from the apparatus by manipulation of the coin controlled apparatus on the part 105 of the customer, the parts occupy the position indicated in Figures 1 and 2, which show the operating lever 10 moved into its foremost position together with the rear controlling bar, and the front controlling bar also 110 moved into its foremost position so that the forwardly facing shoulders 28 of the front controlling bar engage with the rearwardly facing shoulders 22 of the rear controlling bar, and the recesses 19 and 29 of the rear 115 and front controlling bars are arranged in a concentric position relatively to each other and in register with the coin inlet opening immediately above the same. If now an attempt should be made to operate the vending mechanism without placing any coins into the coin apparatus through the inlet opening 321 by merely pushing the front or outer controlling bar inwardly by manually 120 operating the handle 18 this would only per-

mit the front controlling bar 17 to be pushed inwardly until its inner or rear ends engaged with the outwardly facing shoulders 33 on the latch 311, which latter at this time are 5 in their lowered position and stand in the path of the front controlling bar, as shown in Figures 3 and 4, and thereby prevent the rear controlling bar from being moved backwardly or inwardly.

10 If the prospective customer only deposits a single coin through the coin inlet into the coin pocket formed by the co-operating surfaces 19 and 29 of the rear and front controlling bars and then moves the front controlling bar inwardly, the movement of this bar in this direction will be arrested in the same manner in which this occurred when 15 no coin was deposited in the machine and the single coin which was deposited will be 20 simply carried forwardly by the recesses 29 of the front controlling bar and slide into the clearance space 20 formed on the front part of the inner controlling bar below the thin upper front part of the same, as shown 25 in Figures 5 and 6.

If however, two coins of the proper thickness are deposited through the coin opening 321 into the coin pocket formed between the recesses 19 and 29 of the rear and front controlling bars the lower coin will be arranged horizontally in line with the clearance space 20, but the upper coin will be held up high enough so that its peripheral edge will engage with the bearing face 19 at the front 30 end of the rear controlling bar and also with the recesses 29 in the front controlling bar, thereby forming a coupling between the front and rear controlling bars which operates to interlock the same and cause the rear controlling bar to move inwardly in unison with the front controlling bar. The relative position of the controlling bars and the latch 311 is such that during the first part of the inward motion of the rear controlling bar with the front controlling bar, the cam 24 will engage with the front end of the latch 311 and lift the same so that its shoulders 33 are arranged above or out of the path of the inner end of the front controlling bar 35 and thereby avoid obstructing the full inward movement of the front controlling bar. During the last part of the inward motion of the front and rear controlling bars, while the same are thus coupled by the coins between the same, the inner end of the front controlling bar passes inwardly beyond the stops 33 and when these bars reach the extremity of their inward movement which is 40 preferably determined by engagement of the handle 18 of the outer controlling bar with the front end of the bracket 31, then the coin seat formed between the co-operating surfaces of the front and rear controlling bars 45 is arranged within the enclosing casing so that the under side of the coins in the coin

seat at this time are no longer supported and these coins are therefore free to drop out of this coin pocket or seat into the adjacent lower part of the enclosing casing which may serve as a till for this purpose.

This inward or backward movement of both controlling bars while thus coupled only effects an idle inward stroke of the operating lever 10 and merely sets the vending mechanism ready to discharge goods to a

customer during the subsequent forward stroke of the operating lever. This forward motion of the operating lever 10 is effective upon pulling outwardly or forwardly the handle 18 at the front end of the outer controlling bar. During such movement of the outer controlling bar the forwardly facing shoulders 28 of the outer controlling bar engage with the rearwardly facing shoulders 22 of the rear controlling bar, thereby compelling the rear controlling bar to move outwardly in unison with the front controlling bar and causing the operating lever 10 to also move forwardly and actuate the vending mechanism

so as to discharge goods from the machine. During the last part of this forward or outer movement of the rear controlling bar 15 the cam 24 thereon is moved from underneath the latch 311, thereby permitting the latter

to drop by gravity and carry its forwardly facing shoulders 33 downwardly into the path of the rear end of the front controlling bar so as to prevent the latter from being moved rearwardly to such an extent as

would bring the pocket recesses 29 within the casing. If, therefore, a person should deposit only a single coin in the apparatus and move the front controlling bar inwardly this coin would be merely carried

idly inwardly in the guideway 30 but would not be discharged into the till of the casing and would be again drawn outwardly with the front controlling bar whenever the customer pulled the same forwardly, thereby preventing the customer from losing this single coin and enabling him to properly operate the vending mechanism by adding another coin to the one previously deposited and thus obtain the proper height of coins in the coin

pocket necessary to set the vending mechanism for obtaining a discharge of goods therefrom.

In order to enable a customer who has deposited only a single coin in the coin pocket to recover this coin in case he has no additional coin to make up the proper number for effecting a purchase from the machine or if he does not wish to pay more than one coin for the goods offered by the machine, ejecting means are provided which preferably

consist of a lifting disk 35 arranged in a recess 36 in the bottom of the guideway 30 immediately below the coin inlet opening 321. This lifting disk may be operated by

means of a lifting pin or stem 37 extending from the lifting disk 35 through an opening 38 in the bottom of the guideway 30 and provided at its lower end with a button 39 which may be engaged by a finger of the customer for pushing the lifting disk upwardly and thereby raising the coin within the coin pocket upwardly out of the inlet opening 321 where it is accessible to the customer and can be removed by him if he does not wish to make a purchase.

Obviously the clearance space 20 on the rear controlling bar may be made of different heights so as to provide accommodation for more than one coin in the same if it is desired to so organize the coin controlled apparatus that more than two coins are necessary for operating the vending mechanism.

This coin controlled mechanism is not only very simple in construction but the same is also strong and durable so that it is not likely to be injured by persons attempting to tamper with the same and the same is also very reliable in operation so that persons depositing the proper number of coins in the apparatus are certain of obtaining the goods which they are purchasing while other persons who deposit a deficient number of coins in the apparatus will be prevented from operating the vending apparatus but will be assured of the return of the coins which have been deposited less than the required number. This coin controlled mechanism therefore will operate equitably not only with reference to purchasers of goods but also with reference to persons attempting to purchase goods for less than the required amount of coins.

I claim as my invention:

1. A coin controlling apparatus comprising an inner controlling bar adapted to be connected with the part to be actuated, an outer controlling bar movable lengthwise relatively to the inner bar and adapted to be shifted manually, said bars having parts adjacent to each other, and a guide for the adjacent parts of said bars, the outer end of said inner bar being provided on its underside with a clearance space and the adjacent parts of the outer bar being provided with recesses which together with the outer end of said inner bar form a coin pocket.

2. A coin controlling apparatus comprising an inner controlling bar adapted to be connected with the part to be actuated, an outer controlling bar movable lengthwise relatively to the inner bar and adapted to be shifted manually, said bars having parts adjacent to each other, and a guide for the adjacent parts of said bars, the outer end of said inner bar being provided on its underside with a clearance space and the adjacent parts of the outer bar being provided with recesses which together with the outer end of said inner bar form a coin

pocket, and said guide being provided with a coin inlet opening in its top.

3. A coin controlling apparatus comprising an inner controlling bar adapted to be connected with the part to be actuated, an outer controlling bar movable lengthwise relatively to the inner bar and adapted to be shifted manually, said bars having parts adjacent to each other and a guide for the adjacent parts of said bars, the outer end of said inner bar being provided on its underside with a clearance space and the adjacent parts of the outer bar being provided with recesses which together with the outer end of said inner bar form a coin pocket, and said inner bar being provided with an inwardly facing shoulder and said outer bar being provided with an outwardly facing shoulder adapted to engage the inwardly facing shoulder of said inner bar.

4. A coin controlling apparatus comprising an inner controlling bar adapted to be connected with the part to be actuated, an outer controlling bar movable lengthwise relatively to the inner bar and adapted to be shifted manually, said bars having parts adjacent to each other, a guide for the adjacent parts of said bars, the outer end of said inner bar being provided on its underside with a clearance space and the adjacent parts of the outer bar being provided with recesses which together with the outer end of said inner bar form a coin pocket, and said inner bar being provided with an inwardly facing shoulder and said outer bar being provided with an outwardly facing shoulder adapted to engage the inwardly facing shoulder of said inner bar, and detent means adapted to prevent inward movement of the outer bar and to be shifted into its inoperative position by motion of the inner bar.

5. A coin controlling apparatus comprising an inner controlling bar adapted to be connected with the part to be actuated, an outer controlling bar movable lengthwise relatively to the inner bar and adapted to be shifted manually, said bars having parts adjacent to each other, a guide for the adjacent parts of said bars, the outer end of said inner bar being provided on its underside with a clearance space and the adjacent parts of the outer bar being provided with recesses which together with the outer end of said inner bar form a coin pocket, and said inner bar being provided with an inwardly facing shoulder and said outer bar being provided with an outwardly facing shoulder adapted to engage the inwardly facing shoulder of said inner bar, and detent means adapted to prevent inward movement of the outer bar and to be shifted into its inoperative position by motion of the inner bar, said detent means comprising a swinging latch having a forwardly facing

shoulder adapted to be engaged by the inner end of said outer bar and a cam on said inner bar adapted to engage said latch and move the same with its shoulder out of the 5 path of said outer bar.

6. A coin controlling apparatus comprising an inner controlling bar adapted to be connected with the part to be actuated, an outer controlling bar movable lengthwise 10 relatively to the inner bar and adapted to be shifted manually, said bars having parts adjacent to each other; a guide for the adjacent parts of said bars, the outer end of said inner bar being provided on its underside with a clearance space and the adjacent parts of the outer bar being provided with recesses which together with the outer end of said inner bar form a coin pocket, and 15 said guide being provided with a coin inlet opening in its top, and means for ejecting a coin from said pocket.

7. A coin controlling apparatus comprising an inner controlling bar adapted to be connected with the part to be actuated, an outer controlling bar movable lengthwise 25 relatively to the inner bar and adapted to be shifted manually, said bars having parts adjacent to each other, a guide for the adjacent parts of said bars, the outer end of said inner bar being provided on its underside with a clearance space and the adjacent parts of the outer bar being provided with recesses which together with the outer end of said 30

inner bar form a coin pocket, and said guide being provided with a coin inlet opening in 35 its top, and means for ejecting a coin from said pocket, comprising a lifting plate arranged in the lower part of said guide below said coin inlet opening and a lifting stem projecting from the underside of said 40 plate downwardly through said guide.

8. A coin controlling apparatus comprising a longitudinally reciprocating inner bar adapted to be connected with the part to be actuated and provided on its upper side 45 with a releasing cam, on its opposite sides with inwardly facing shoulders and having its outer end provided with a clearance space on the underside thereof, a hand operated outer bar provided with a longitudinal slot which receives the outer part of the inner bar and which has recesses forming 50 with the outer end of said inner bar, a pocket adapted to receive coins, a guideway for said bars having an opening in its top 55 for introducing coins into said pocket and extending across the lower end of said pocket to form a bottom therefor, and a locking latch pivoted on a fixed support having a shoulder adapted to engage the inner end of said hand operated bar and adapted to be lifted by said cam for moving the latch 60 out of the path of said hand operated bar.

In testimony whereof I affix my signature.

ROY RAY FOGELSONGER.
